ROLLER SKATE WHEEL GRINDER

John P. Gleba, East Hartford, Conn.

Application November 26, 1940, Serial No. 367,273

5 Claims. (Cl. 51—123)

This invention relates to machines for grinding and reconditioning the wheels of roller skates. The object of the invention is to provide a simple, relatively inexpensive, easily manipulated machine into which roller skates can be quickly placed and the wheels, usually made of wood or fiber, ground true after they are worn out of round, or become rough or grooved, or the faces of their peripheries have worn out of parallelism with their axes.

Fig. 1 of the accompanying drawing shows a side elevation of the machine with parts in vertical section.

Fig. 2 shows an elevation looking toward the left-hand end of the machine.

Fig. 3 shows a plan view of the left-hand end of the machine.

Fig. 4 shows a longitudinal section of the skate holding end of the machine.

The machine has a rectangular base 1 mounted on which is an electric motor 2 with a grinding wheel 3, having an abrasive radial face, and a dust removing fan 4 attached to the armature of the motor, also a guard and dust collector 5 arranged about the fan and the grinding wheel.

On the base and facing the grinding wheel is a carriage 6 that is slidably mounted on rods 7 which extend transversely of the base through lugs 8 on the under side of the carriage, the rods 7 being supported by lugs 9 which extend up from the base. The carriage is movable on the rods 7 transversely of the base and transversely of the face of the grinding wheel, by means of a lever 10 which is pivoted to the base and is connected with the carriage by a link 11.

On the carriage is a table 12 that is movable longitudinally of the base and carriage or toward and from the face of the grinding wheel, on rods 13 which extend through lugs 14 on the under side of the table, the rods 13 being supported by lugs 15 which project up from the carriage. The table is movable back and forth on the rods 13 by means of a screw 16 that passes through a lug 17 which extends upward from the carriage, and is threaded through a lug 18 which projects downward from the table. This screw is provided with a handle 19 by means of which it may be turned.

On each side of the table at the end adjacent to the face of the grinding wheel are two upright arms 20 which at their upper ends have sockets 21 for receiving the ends of a skate wheel axle 22. The arms are shown as of such length and the sockets are so positioned that the skate wheel axle will be supported with its axis above

and at right angles to the axis of the grinding wheel. Preferably the socket on one side is fixed in its supporting arm, and the socket on the other side is adjustable in and out, being swivelled to the end of a screw 23 that is threaded through its supporting arm and is provided with a hand wheel 24 by means of which it may be easily turned.

In using the grinder the adjustable socket 10 is drawn outward allowing the ends of the axle 22 of the skate wheels 25 that are to be ground, to be placed in the sockets and then the adjustable socket is moved inward by turning the hand wheel 24 so that the wheel axle will be held and the skate supported at one end by the sockets in a substantially vertical position. In this position the lower end of the skate plate 26 rests against an upright rib 27 at the end of the table between the arms 20. With the skate thus retained the table is moved forward by turning the handle 19 until two of the skate wheels engage the face of the rotating grinding wheel, and then by means of the lever 10 the carriage which supports the table with the skate is moved back and forth transversely so as to cause the peripheries of those skate wheels to traverse the face of the grinding wheel. When one pair of skate wheels is ground the skate is removed and turned end for end and the other pair of skate wheels is ground. The fan 4, which may be of any common type and turns with the motor shaft, completely removes the dust and particles ground from the skate wheels and causes it to blow out of the opening 28 in the wall of the guard 5. The act of locating and removing the skate is easy and rapid, the manipulation of the carriage and table is simple, and the worn faces of the skate wheels are quickly restored to good serviceable condition by the cooperative action of the revolutions of the grinding wheel and rotatory and transverse movements of the skate wheels across the rotating grinding wheel.

The invention claimed is:

1. A grinder for conditioning the peripheral surfaces of pairs of roller skate wheels which comprises a base, a motor mounted on the base, a grinding wheel with an abrasive radial face fixed on the motor shaft and rotating in a constant plane, a carriage mounted on the base and movable in a plane transverse thereof and of the abrasive face of the grinding wheel, a table mounted on the carriage and movable longitudinally of the base and toward and from the abrasive face of the grinding wheel, a pair of arms ex-

tending upward from the end of the table that is adjacent to the abrasive face of the grinding wheel, said arms being spaced apart and moving together in the same direction toward and from the plane of the abrasive face of the grinding wheel when the table is moved longitudinally, and means at the upper ends of said arms for receiving and retaining the ends of the wheel axle of a roller skate with the axle extending transversely of the abrading face of the grinding wheel and the peripheries of the wheels on said axle in position to be subjected to the abrasive face of the grinding wheel.

2. A grinder for conditioning the peripheral surfaces of pairs of roller skate wheels which comprises a base, a motor mounted on the base, a grinding wheel with an abrasive radial face fixed on the motor shaft and rotating in a constant plane, a carriage mounted on the base and movable in a plane transverse thereof and of the abrasive face of the grinding wheel, a table mounted on the carriage and movable longitudinally of the base and toward and from the abrasive face of the grinding wheel, a pair of arms extending upward from the end of the table that is adjacent to the abrasive face of the grinding wheel, said arms being spaced apart and moving together in the same direction toward and from the plane of the abrasive face of the grinding wheel when the table is moved longitudinally, and sockets at the upper ends of said arms for receiving and retaining the ends of the wheel axle of a roller skate with the axle extending transversely of the abrading face of the grinding wheel and the peripheries of the wheels on said axle in position to be subjected to the abrasive radial face of the grinding wheel; at least one of said sockets being adjustable in line with the wheel axle it is to receive.

3. A grinder for conditioning the peripheral surfaces of pairs of roller skate wheels which comprises a base, a motor mounted on the base, a grinding wheel with an abrasive radial face fixed on the motor shaft and rotating in a constant plane, a carriage mounted on the base and movable in a plane transverse thereof and of the abrasive face of the grinding wheel, a table mounted on the carriage and movable longitudinally of the base and toward and from the abrasive face of the grinding wheel, a pair of arms extending upward from the end of the table that is adjacent to the abrasive face of the grinding wheel, said arms being spaced apart and moving together in the same direction toward and from the plane of the abrasive face of the grinding wheel when the table is moved longitudinally, means at the upper ends of said arms for receiving the ends of the wheel axle of a roller skate, and an abutment extending upward from

the table between said arms for the engagement of the end of the skate and adapted to hold the skate with the peripheries of the wheels on said axle in position to be subjected to the abrasive radial face of the grinding wheel.

4. A grinder for conditioning the peripheral surfaces of pairs of roller skate wheels which comprises a base, a motor mounted on the base, a grinding wheel with an abrasive radial face fixed on the motor shaft and rotating in a constant plane, a carriage mounted on the base and movable in a plane transverse thereof and of the abrasive face of the grinding wheel, a lever pivoted to the base and connected to the carriage for moving the carriage, a table mounted on the carriage and movable longitudinally of the base and toward and from the abrasive face of the grinding wheel, threaded means connecting the carriage and the table for moving the carriage, a pair of arms extending upward from the end of the table that is adjacent to the abrasive face of the grinding wheel, said arms being spaced apart and moving together in the same direction toward and from the plane of the abrasive face of the grinding wheel when the table is moved longitudinally, and means at the upper ends of said arms for receiving and retaining the ends of the wheel axle of a roller skate with the axle extending transversely of the abrading face of the grinding wheel and the peripheries of the wheels on said axle in position to be subjected to the abrasive radial face of the grinding wheel.

5. A grinder for conditioning the peripheral surfaces of pairs of roller skate wheels which comprises a base, a motor mounted on the base, a grinding wheel with an abrasive radial face fixed on the motor shaft and rotating in a constant plane, a carriage mounted on the base and movable in a plane transverse thereof and of the abrasive face of the grinding wheel, a table mounted on the carriage and movable longitudinally of the base and toward and from the abrasive face of the grinding wheel, a pair of arms extending upward from the end of the table that is adjacent to the abrasive face of the grinding wheel, said arms being spaced apart and moving together in the same direction toward and from the plane of the abrasive face of the grinding wheel when the table is moved longitudinally, means at the upper ends of said arms for receiving and retaining the ends of the wheel axle of a roller skate with the axle extending transversely of the abrading face of the grinding wheel and the peripheries of the wheels on said axle in position to be subjected to the abrasive radial face of the grinding wheel, a fan fixed to the motor shaft, and a guard and dust collector about the grinding wheel and fan.
